UNITED STATES PATENT OFFICE

105,103

DESIGN FOR A FORM CLAMP

Bror Hillberg, Chicago, Ill., assignor to Universal Form Clamp Co., Chicago, Ill., a corporation of Illinois

Application October 19, 1936, Serial No. 65,357

Term of patent 14 years

To all whom it may concern:

Be it known that I, Bror Hillberg, a citizen of the United States, residing in Chicago, county of Cook, and State of Illinois, have invented a new, original, and ornamental Design for a Form Clamp, of which the following is a specification, reference being had to the accompanying drawing forming a part thereof.

Fig. 1 is a top plan; and
Fig. 2 is a side elevation of a form clamp embodying my new design.

I claim:

The ornamental design for a form clamp substantially as shown.

BROR HILLBERG.
